Sigmund Herzog

UNITED STATES PATENT OFFICE.

JOSEPH WM. LE MAIRE, OF NEW YORK, N. Y.

PRIMING DEVICE.

Application filed December 24, 1921. Serial No. 524,723.

To all whom it may concern:

Be it known that I, JOSEPH WM. LE MAIRE, a citizen of the United States, and resident of the city of New York, in the 5 county of New York and State of New York, have invented certain new and useful Improvements in Priming Devices, of which the following is a specification.

The present invention relates to improvements in starting devices for internal combustion engines, and more particularly to that type of starting devices which is intended to be used in connection with engines upon motor vehicles, although it will be understood that it is applicable to engines used otherwise.

The main object of the invention is to provide a simple and inexpensive device, by the use of which a sufficient quantity of gasoline, to prime the engine, may be introduced into the cylinders of the engine without the necessity of opening the hood of the motor vehicle to turn the pet-cocks of the various priming cups.

Another object of the invention is to so construct the priming device that it may be used at the same time as a means for introducing air into the intake-manifold of the engine, said air meeting the stream of combustible mixture from the carburetor and serving to produce a more uniform mixture.

With these and other objects in view, which will more fully appear as the nature of the invention is better understood, the 35 same consists in the combination, arrangement and construction of parts hereinafter described, pointed out in the appended claims and illustrated in the accompanying drawings, it being understood that many 40 changes may be made in the size and proportion of the several parts and details of construction within the scope of the appended claims, without departing from the spirit or sacrificing any of the advantages of the 45 invention.

One of the many possible embodiments of the invention is illustrated in the accompanying drawings, in which:—

Figure 1 is a central vertical section taken 50 through a priming device constructed in accordance with the present invention; Fig. 2 is a similar view, partly in elevation, showing the elements in other positions; and Fig. 3 is a section, on a larger scale, taken 55 through the piston of the priming device.

In the drawings, the numeral 10 indicates

a pump cylinder, having a flange 11 adjacent its inner or rear end, said flange abutting against one side of the dash-board 12 of an automobile and co-operating with a sleeve 13, 60 for securing the said cylinder to the said dash-board. The sleeve is provided with exterior screw-threads 14, meshing with interior screw-threads 15 in the cylinder, it having furthermore a shoulder 16, that bears 65 against a washer 18 on the operator's side of the dash-board. It is, of course, understood that other means may be provided for attaching the said cylinder to the dash-board, the one herein disclosed being shown for 70 purposes of illustration only. The opposite or front end of the cylinder is closed by a head 19, provided with a pump outlet 20. Around the said outlet is formed on the said head a screw-threaded nipple 21, which is 75 joined, by a coupling 22, with a pipe 23, leading to the intake-manifold of the internal combustion engine on the motor vehicle. A suitable distance in rear of the head 19 is 80 formed in the cylinder a pump inlet 24, in the form of a screw-threaded nipple, to which is fastened a valve casing 25, the latter being joined by a coupling 26 with a pipe 27. This pipe leads to the main fuel supply pipe of the engine. In the pump cylinder 85 is mounted a piston 28 upon a piston rod 29. This piston rod extends through the sleeve 13, which constitutes the rear head of the pump cylinder, and terminates in a handle 30, the latter being disposed on the operator's side of the dash-board. The piston may be of any suitable construction and material. In the case illustrated in the drawings, it consists of a plurality of alternately arranged packing disks 31 and metallic disks 90 32, the latter being of smaller diameter than the packing disks. To hold these disks on the piston rod, the latter is provided with a shoulder 33, against which one of the said disks bears, the outermost metallic disk, denoted by the numeral 32', being held in place 95 by a cotter pin 34, or similar fastening means. In front of the disks 32' is mounted a packing member 35, adapted to bear against the inner face of the front head 19 of the cylinder. The front end of the piston rod is 100 screw-threaded, as shown at 36, said threads being adapted to mesh with interior threads 36' of the pump outlet 20 in the cylinder head 19.

In the valve casing 25 is disposed a check valve 37, which is under the tension of a

spring 38, said valve opening toward the pump cylinder.

A check valve 39 is mounted in the cylinder head 19 for controlling the pump outlet. This valve is under the tension of a spring 40 and is adapted to open toward the pipe 23. In the cylinder head 19 is formed a screw-threaded opening 41, into which is fitted a cock 42, the plug 43 of which is mounted upon a bar 44, the latter extending through the dashboard 12 and being provided on the operator's side of the said dashboard with a handle 45. The screw-threaded opening 41 communicates with the pump outlet 20 in rear of the check valve 39. The inlet to the cock 42 is covered by a screen 46, for a purpose hereinafter to be described.

The operation of this device is as follows: In the positions of the elements shown in Fig. 1 of the drawings, the threads of the piston rod mesh with those of the pump outlet, the packing washer 35 snugly fitting against the inner face of the front head 19 of the cylinder. In order to prime the engine, the piston rod is first turned so as to unmesh its threads from the threads in the pump outlet. The piston is then drawn rearwards until its shoulder 33 abuts against the sleeve 13, whereby liquid fuel is drawn through the pipe 27 into the pump cylinder. The piston is then moved in the opposite direction, that is to say upon its expelling stroke. The fuel in the cylinder is thus injected through the pipe 23 into the intake-manifold, from which it is drawn into the cylinders of the engine. When the piston has reached the end of its expelling stroke, it is turned to screw the piston rod into the pump outlet, bringing the packing washer 35 into proper engagement with the front head 19 of the pump cylinder. On the suction stroke of the piston the check valve 39 is held on its seat and the check valve 37 unseated. On the expelling stroke, on the other hand, the valve 37 is seated, preventing a flow of the fuel into the pipe

37, and the check valve 39 unseated. When the device is used for priming purposes, the plug 43 of the cock 42 is set to closing position. Although a single operation of the primer should be sufficient under ordinary conditions, the operation now described may be repeated as often as desired according to the requirements.

If air is to be introduced into the intake-manifold of the engine, the plug of the cock 42 is set to open position, the piston 28 being held locked in the position shown in Fig. 1 of the drawings. During each suction stroke of the pistons in the cylinders of the engine, the check valve 39 is unseated and air is drawn through the cock 42 and pipe 23 into the manifold, where it meets the stream of combustible mixture from the carburetor, thereby producing a more uniform mixture. The screen 46 on the cock prevents impurities from entering the intake manifold.

What I claim is:—

In a device of the character described, the combination with a pump cylinder having an inlet communicating with a supply of liquid hydrocarbon and an outlet connected with the intake-manifold of an internal combustion engine, said outlet extending through the front head of said cylinder and being screw-threaded, of a piston in said cylinder, a piston rod connected with said piston having a screw-threaded portion projecting in front of said piston and adapted to engage said screw-threaded pump outlet, thereby closing said outlet and holding said piston against accidental movement, a check valve controlling said inlet, a check valve controlling said outlet, and a cock-controlled passage for establishing a communication between the atmosphere and said cylinder in rear of the check valve controlling said outlet.

Signed at New York, in the county of New York and State of New York, this 12th day of December, A. D. 1921.

JOSEPH WM. LE MAIRE.
